Inventor:

UNITED STATES PATENT OFFICE.

JOHN WELSH, OF GREEN BAY, WISCONSIN.

SHIPPING AND DISPENSING PACKAGE.

1,003,558.

Specification of Letters Patent.

Patented Sept. 19, 1911.

Application filed October 15, 1909. Serial No. 522,755.

To all whom it may concern:

Be it known that I, JOHN WELSH, a citizen of the United States, residing at Green Bay, in the county of Brown and State of Wisconsin, have invented certain new and useful Improvements in Shipping and Dispensing Packages, of which the following is a specification.

The object of my invention is to provide a dispensing carton for sheets of tissue paper, providing the same with means whereby single sheets may be delivered therefrom. The carton is designed for use as a shipping package, and also for use as a dispensing device.

In the drawings—Figure 1 is a perspective view of one form of my invention. Fig. 2 is a longitudinal section through the structure shown in Fig. 1. Figs. 3, 4 and 5 are perspective views of devices similar to that shown in the preceding figures, but provided with modified means for delivering single sheets of paper. Figs. 6 and 7 are fragmentary views showing additional modifications of delivering mechanism. Figs. 8 and 9 are perspective views of a further modification in which different means are employed for keeping the outer sheet of the pile in contact with the apertured side of the carton or casing.

Referring to the device illustrated in Figs. 1 and 2, the carton or exterior casing may consist of an ordinary paste-board box, one side of which is cut away to form an aperture as indicated at 1. Within the casing is a backing or false bottom 2 which is yieldingly pressed toward the apertured side 3 of the carton by a spring 4 which occupies the space between the backing 2 and the side 5 of the carton opposite the side 3. Any convenient means may be adopted for yieldingly pressing the backing 2 toward the side 3 of the casing. In the present instance I have shown a spiral spring 4 for this purpose. The pile of paper 6 is placed in the casing, preferably before the latter is closed up, between the backing 2 and the apertured side 3. A friction member 7, preferably faced with rubber 8, sand paper or other frictional material, is yieldingly connected to the casing by a spring 9, the spring 9 and friction member 8 lying flat against the upper side of the carton in such manner as not to project therefrom any considerable distance. The spring 9 may be connected to the carton in any suitable manner as by threading

its end through the material of which the carton is composed. Normally the friction member 7 lies adjacent one end of the aperture 1. By pressing inwardly with the hand upon the friction member 7 and drawing it across the upper sheet of the pile 6 in the direction indicated by the arrow, the upper sheet will be buckled as indicated at 10 in Fig. 2 whereupon the fold 10 can be conveniently grasped between the fingers and the sheet removed from the carton. As the sheets are successively removed from the outer side of the pile, the spring 4 or other device employed will force the backing 2 outwardly thus keeping the outer sheet snugly against the inner surface of the side 3 of the casing. It will not be found necessary in all cases to employ the friction member 7 as the sheets can be conveniently removed from the carton by means of the fingers alone, it being merely necessary to provide the carton with the opening 1 through which the outer sheet can be reached.

In Fig. 3 I have illustrated a form of the device similar to that shown in Figs. 1 and 2, except that the friction member 11 is mounted upon a piece of spring wire 12 which extends across the top of the carton 85 downward upon the outer face of the sides where it is formed into spring coils 13, the extreme ends 14 being secured to the carton either by being threaded therethrough or by means of paper pasted thereover. The 90 spring coils 13 serve to return the friction member 11 to the position illustrated in Fig. 3, but permit it to be moved across the face of the pile for the purpose of removing a sheet as explained in connection with the 95 forms shown in Figs. 1 and 2.

In Fig. 4 I have shown a forked spring, the arms of which are connected by a coil. The spring is located upon the inner side of the end of the carton and its upper member 100 15 is secured thereto. A flexible cord 16 is secured to the free arm 17 of the spring and extends around the end of the pile of sheets in the carton to the aperture in the side thereof. A friction member 18 is attached to the free end of the flexible cord. Upon manipulating the friction member 18 the spring 17 will yield permitting said friction member to be swept across the upper sheet of the pile and upon its release the friction 110 member will return to its normal position. In Fig. 5 I have shown two friction mem-

bers 19 connected by means of a spring 20. Each arm of the spring 20 is given a right-
angular bend at 21 and the downwardly pro-
jecting part 22 of the spring is secured to
the inside of the side wall 23 of the carton.
5 Preferably the spring 20 is coiled at the
junction of the two arms for the purpose of
increasing its resiliency. In operation, the
finger and thumb will be placed upon the re-
10 spective friction pads 19 and these pressed
against the paper and moved toward each
other. This will cause the paper to buckle
between the friction pads 19, withdrawing
the ends of the sheet from the ends of the
15 carton, after which the fingers may release
the pads 19 and seize the fold of paper be-
tween them.

The form shown in Fig. 6 is similar to
those previously described, except in the
20 mounting of the friction pad 24. In this
instance the pad 24 is mounted upon the end
of a straight piece of spring wire 25 secured
at 26 to the side of the carton adjacent the
aperture.

25 In Fig. 7 I have shown a friction roller 27
mounted upon a U-shaped piece of wire 28
secured to the side of the carton at 29. The
friction roller 27 may be rotated by means
of the finger, thus imparting movement to
30 the outer sheet of paper and causing it to
buckle.

In Figs. 8 and 9 I have illustrated a form
of the device in which instead of forcing the
package of paper forwardly against the
35 apertured side of the carton, I provide
means for moving the parts of the side adja-
cent the aperture inward toward the pile of
sheets as they are removed. The sections
31, 31 of the apertured side of the carton

are severed from the sides 30, 30 leaving 40
connections with the ends to form hinges.
A friction pad and spring similar to that
illustrated in Fig. 1 may be employed, and
any convenient means may be utilized for
drawing the free edges of the sections 31, 31 45
inwardly as sheets are removed from the
pile of paper 6. In the particular structure
illustrated in Figs. 8 and 9 I have shown an
elastic cord 32 secured at its ends 33 to the
free corners of the sections 31, and interme-
diately its ends passing through eyelets 34
secured to the base of the carton. In Fig. 9
the position of the parts is illustrated after
about half of the sheets have been removed.

50 While I have described and illustrated 55
several specific forms of my invention it
will be apparent that the principle thereof
is independent of the particular mechanisms
shown and may be applied in structures of
widely different form. 60

I claim:

A shipping and dispensing carton for
sheets of paper having in one wall an aper-
ture extending the full width of the inclosed 65
sheets of paper, a friction member, means
connecting said friction member to said car-
ton but permitting it to have a reciprocatory
movement over said aperture to buckle the
outermost sheet of paper, and means for
keeping the paper pressed against the wall 70
containing the aperture.

In testimony whereof, I have subscribed
my name.

JOHN WELSH.
